UNITED STATES PATENT OFFICE.

WILLIAM E. HAWTHORNE, OF PLYMOUTH, MICHIGAN, ASSIGNOR TO DAISY MANUFACTURING COMPANY, OF PLYMOUTH, MICHIGAN, A CORPORATION OF MICHIGAN.

SPRING-GUN.

1,114,610.

Specification of Letters Patent.

Patented Oct. 20, 1914.

Application filed May 31, 1913. Serial No. 771,033.

To all whom it may concern:

Be it known that I, WILLIAM E. HAWTHORNE, a citizen of the United States of America, residing at Plymouth, in the county of Wayne and State of Michigan, have invented certain new and useful Improvements in Spring-Guns, of which the following is a specification, reference being had therein to the accompanying drawings.

10 The invention relates to spring guns in which the power for propelling the projectile is first stored by manual manipulation.

It is one of the objects of the invention to provide an actuating mechanism for the 15 power storage, which simulates the so-called pump mechanism employed on cartridge guns.

It is a further object to obtain a construction having certain advantageous features 20 as hereinafter set forth.

In the drawings: Figure 1 is an elevation of the gun; Fig. 2 is a longitudinal section through a portion of the barrel, showing the power storage mechanism in its initial position; and Fig. 3 is a similar view showing the power stored but before the return of the parts to position for firing, and also showing in dotted lines the said parts returned.

30 A is the barrel of the gun, B is the power storage spring therein, C an abutment against which said spring bears, D a plunger, and E the plunger shank extending through said abutment and provided 35 with a head E' for engaging the sear F. The gun belongs to that type in which the spring is compressed by a forward movement of the abutment, which is subsequently returned after engagement of the shank 40 with the sear. Such guns are, however, usually operated by levers, while with the present invention, as above stated, a longitudinally slidable actuating mechanism is provided, the construction being as follows:

45 The abutment C is mounted in a hollow slide G, which is movable longitudinally of the barrel and is provided with a rack H preferably formed by pins extending between the opposite sides of the slide. I is 50 a segmental rack engaging the rack H, which is pivoted at J and is provided with a forwardly-extending arm K connected by a pivotal link L with an actuating member M. This actuating member is a block or hand grip, which is slidable longitudinally

of the barrel, being preferably mounted upon a rod O arranged parallel to the barrel. Thus, by pulling rearward upon the member M, the link L and arm K will swing downward partially rotating the segmental rack 60 I and moving the rack H and slide G forward. This will advance the sear which is pivotally mounted at P upon the slide G until it engages with the head E' on the shank E. The actuating member is then 65 moved forward again to return the slide G, carrying with it the compressed spring, plunger and shank.

In performing the operation just described, it is important to prevent releasing 70 of the spring before the return of the slide, as otherwise the recoil of said spring would kick the slide backward against the stock Q. Such a result I have guarded against by a construction in which the sear is separable 75 from the trigger and is only in operative relation with the latter when the slide is fully returned. Thus, as shown, R is the trigger which is pivoted at R' in a fixed position within the gun barrel. The sear 80 F, as before stated, is pivoted at P upon the slide G, and a rearwardly-extending arm F' lies in the path of the trigger when the parts are in normal position.

S is a spring for yieldably holding the 85 sear in position of engagement.

When the slide is moved forward in the operation above described, the arm F' is withdrawn from the path of the trigger R, and therefore any movement of the trigger 90 will be ineffective to discharge the gun until the parts are returned to normal position.

With the construction as described in operation, to store the power the actuating member M is drawn rearward, which will 95 swing downward the links L and arms K, rotating the rack I and moving the slide G forward until the head E' engages the sear. The reverse movement of the actuating member M returns the slide and sear to normal position, in which the latter is in the path of the trigger R and consequently upon the pulling of the trigger the plunger is released to be moved forward under the tension of the spring. 100

105 What I claim as my invention is:

1. In a gun, the combination of a power storage spring, a trigger, an abutment movable to compress said spring and returnable to its initial position for firing, a sear for 110

engaging the trigger carried by said abutment and in operative relation to be released by the trigger only when the abutment is in said initial position.

5. 2. In a gun, the combination of a power storage spring, an abutment, mechanism for moving said abutment forward to compress said spring and for then returning said abutment to normal position, a trigger for 10 releasing said spring, and a sear controlling the release of said spring, separable from said trigger during the forward movement of said abutment and restored to operative relation with said trigger upon the return 15 of said abutment.

3. In a gun, the combination of a power storage spring, an abutment therefor, mechanism for moving said abutment forward to compress said spring and to then 20 return the abutment to its normal position, a trigger for releasing said spring, and a sear movable with said abutment out of operative relation with said trigger and restored into operative relation upon the re- 25 turn of said abutment.

4. In a gun, the combination with a barrel, of a power storage spring therein, an abutment movable forward in said barrel to compress said spring and then returnable 30 with said spring to its initial position, an actuating member slidale parallel to the axis of said barrel, and connections between said actuating member and abutment for transmitting reciprocatory movement from

the former to the latter in reverse directions. 35

5. In a gun, the combination with the barrel, of a power storage spring, a slidale abutment for said spring within said barrel movable forward to compress the spring, a 40 sear carried by said movable abutment for retaining said spring in compressed condition, an actuating member slidale parallel to the axis of said barrel, connections between said actuating member and said abutment for imparting reverse reciprocatory movement from one to the other, and a trigger from which said sear is withdrawn in the forward movement of said abutment 45 and to which it is returned by the reverse movement. 50

6. In a gun, the combination with the barrel, of a plunger, a spring for actuating said plunger, a movable abutment other than said plunger for said spring, an actuating 55 member arranged exteriorly of the barrel and slidale longitudinally of said barrel, and connections between said actuating member and abutment for moving the latter to compress the spring upon a rearward 60 movement of the actuating member.

In testimony whereof I affix my signature in presence of two witnesses.

WILLIAM E. HAWTHORNE.
